UNITED STATES PATENT OFFICE.

JOHN T. WAYLAND AND TOM D. JONES, OF KANSAS CITY, MISSOURI.

AUTOMATIC TRAFFIC SIGNAL.

Application filed November 14, 1927. Serial No. 233,171.

- Our invention relates to automatic traffic signals and one object is to provide a signal of this character which may be employed to advantage at the intersection of rural roads where electricity is not available for power and illuminating purposes, and with that end in view we have provided a signal with a self-contained lamp and a self-contained power mechanism.
- In carrying out our invention we employ a rotary element for displaying signals indicating Go, Neutral, Stop and Neutral, together with mechanism for intermittently driving said element so that the latter will pause during suitable intervals to better display the respective signals.
- In order that the invention may be fully understood, reference will now be had to the accompanying drawings, in which:
- Fig. 1 is a broken side elevation partly in section of our automatic signal.
- Fig. 2 is a horizontal section on line 2—2 of Fig. 1.
- Fig. 3 is a horizontal section on line 3—3 of Fig. 1.
- Fig. 4 is a modification of the rotary signal element.
- Fig. 5 is an irregular horizontal section on line 5—5 of Fig. 1.
- Fig. 6 is an irregular horizontal section on line 6—6 of Fig. 1.
- In carrying out our invention we provide a casing 2 having a base 4 and a top 6. Access is had to the interior of the casing 2 through a door 8 which has openings equipped with lenses 10 and 12 arranged at right angles to each other as shown by Fig. 2. The upper portion of the casing 2 has openings equipped with lenses 14 and 16, the former of which is arranged diametrically opposite to the lens 10 while the lens 16 is arranged diametrically opposite to the lens 12. All of said lenses are arranged on the same horizontal plane.
- 18 designates a rotary table which is arranged within the casing 2 and carries a transparent signal element 20 which is located centrally between the lenses 10, 12, 14 and 16. The signal element 20 is of tubular form and may have any suitable cross sectional configuration. In Fig. 1 we have shown said signal element 20 of circular configuration and vertically corrugated as disclosed by Fig. 2 and of octagonal configuration as shown by Fig. 4. The signal element 20 has an uneven surface in order to better reflect the light cast thereon from the headlights of approaching motor vehicles, in the event the lamp hereinafter described should become extinguished. Any suitable signals indicating Stop, Neutral, Go and Neutral may be formed upon the element 20, but in the present instance we prefer to indicate the signal Go with green, the Neutral with yellow, and the Stop with red, said colors being arranged to divide the element 20 longitudinally into eight equal parts, with two diametrically opposed green signals, two diametrically opposed red signals, and two sets of diametrically opposed yellow signals. The colored portions are approximately equal in width to the width of the lenses 10, 12, 14 and 16 and so related to each other that when the green signals appear at say the lenses 10 and 14 the red signals will show through the lenses 12 and 16, while the four yellow signals will be hidden by the casing 2 and the door 8, and when the yellow signals appear at the four lenses the green and red signals will be hidden by the casing 2 and the door 8 so that there will be no confusion of signals.
- The signal element 20 may be illuminated by any suitable means, but in the drawings we have shown a centrally disposed lamp 22 which may be either of the kerosene or acetylene type and provided with a tank 24 adapted to rest upon a stationary shelf 26 mounted upon a stationary shaft 28 which is secured at its lower end to a housing 30 fitting within the lower portion of the casing 2. In order to center the tank 24 upon the shelf 26 the latter projects upwardly into a recess 34 in the bottom of the former.
- The table 18 is rotated step by step by means of a ratchet wheel 36 fixed to the under side thereof. Said ratchet wheel is provided with as many teeth as there are colors on the signal element 20 and is rotated step by step a distance equal to the length of each tooth by means of a pawl 38 pivotally mounted upon a lever 40 which is quickly advanced by a spring 42 and slowly retracted by a rotary cam 44. The ratchet wheel 36 is loosely mounted upon the stationary shaft 28 and provided at its under side with a disk 46 containing antifriction ball bearings 48 which travel on top of the housing 30.
- The pawl 38 is prevented from swinging away from the ratchet wheel 36 by means of a downturned lug 50 which engages the rear

side of the lever 40. As the pawl 38 is carried backwardly out of engagement with one ratchet tooth it contacts a stop 41 and is caused thereby to swing into engagement with the succeeding tooth preparatory to advancing the ratchet wheel 36 one step.

The cam 44 is arranged to display the red and green signals through periods of equal duration, and the yellow signals during lesser intervals so that traffic will not be unduly delayed in waiting for said green or red signals to appear. This is accomplished by providing the cam 44 with shoulders 43 and 45, the latter of which may be adjusted 10 towards or away from the former according to the duration desired of said lesser intervals. The shoulder 45 is adjustably held upon the cam 44 by suitable means such as a screw 47 adapted to be threaded into any 15 of the holes 49 in said cam.

The cam 44 is fixedly mounted upon a shaft 52 journaled in the upper portion of the housing 30 and driven by a train of gears which consists of a pinion 64, a small 25 gear 80 intermeshing with said pinion 64, a large gear 54 fixed upon said gear 80, a small gear 82 intermeshing with said gear 54, a large gear 84 fixed upon the small gear 82, a small gear 86 intermeshing with the 30 gear 84, a large gear 88 fixed upon the gear 86, and a small gear 90 intermeshing with the gear 88 and fixed upon the shaft 52. The foregoing train is driven by a spring motor consisting, preferably, of a spiral 35 spring 56 arranged within a drum 58 loosely mounted upon a shaft 60 upon which the pinion 64 is fixedly mounted. The shaft 60 is journaled in the bottom of the housing 30 and a partition 62 in the upper portion of 40 said housing.

One end of the spiral spring 56 is connected to the drum 58 and the other end to the shaft 60 and when run down said spring may be rewound with a set of worm gears 45 consisting of a worm wheel 66 and a worm 68, which latter is fixedly mounted upon a shaft 70 adapted to be rotated with a crank, not shown. The worm wheel 56 is fixedly mounted upon the top of the drum 58 and 50 coacts with the worm 68 in locking said drum from rotation while the spring 56 is unwinding to drive the gear train through the intermediary of the shaft 60. A suitable escapement is provided for regulating the speed of 55 the gear train. In the present instance said escapement consists of a balance-wheel 72, a hair spring 92, a small gear 94 fixed to the balance wheel 72, an anchor 96 for oscillating said gear 94, and an escape-wheel 98 which 60 is alternately engaged by the pallets of said anchor 96. The escape-wheel 98 has a small fixedly mounted gear 100 driven by a large gear 102 fixed upon a shaft 104 driven by the small gear 82.

65 As shown by Fig. 1 the housing 30 fits

within the lower portion of the casing 2 and in the event that repairs or adjustments to the driving mechanism are necessary said housing 30 may be removed through the door 8 after removal of the signal element 20 and 70 the lamp 22.

In the modified form disclosed by Fig. 4, the rotary signal element 20^a is of hexagonal instead of circular shape and has two diametrically-opposed sides 20^b for displaying 75 the green signals, two diametrically-opposed sides 20^c for displaying the red signals, two diametrically-opposed sides 20^d for displaying two of the neutral signals, and two diametrically-opposed sides 20^e for displaying 80 the other pair of neutral signals.

From the foregoing description it is apparent that we have provided a signal apparatus of the character described which is well adapted for the purpose intended, and 85 while we have shown a preferred form of the invention and a modification of the rotary signal element, we reserve all rights to such other changes and modifications as properly fall within the spirit and scope of 90 the invention as claimed.

Having thus described our invention, what we claim and desire to secure by Letters Patent, is:

1. In a device of the character described, 95 a corrugated tubular signal element, a table upon which said signal element is mounted, and mechanism for rotating said table step by step.

2. In a device of the character described, 100 a tubular element having signal colors indicating Go, Neutral, Stop and Neutral, the same colors being diametrically-opposed, mechanism for rotating said element at intervals and including a cam, adjustable 105 means mounted upon said cam for changing the length of the intervals, and a casing enclosing the tubular element and said mechanism and provided with openings through which the signal colors are successively displayed.

3. In a device of the character described, 110 a transparent signal element, a table upon which said signal element is mounted, mechanism for rotating said table step by step, a shelf disposed above said table, and a lamp 115 mounted upon said shelf and having a recess in its lower portion for the reception of the upper part of said shelf.

4. In a device of the character described, 120 a tubular signal element, a table upon which said signal element is mounted, pawl and ratchet mechanism for rotating said table step by step, a cam having fixed and adjustable shoulders for actuating said pawl 125 and ratchet mechanism, a train of gears for driving said cam, a shaft provided with a pinion for driving said train of gears, a drum through which said shaft extends, a spiral spring enclosed within said drum and 130

secured thereto and to said shaft, worm gearing whereby said drum may be rotated to wind the spring, and a casing enclosing all of the aforementioned parts and provided with openings through which the tubular signal element may be viewed.

5. In a device of the character described, a tubular signal element having an uneven surface, and means for rotating said element step by step.
- 10 6. In a device of the character described,

a signal element, mechanism including a cam for rotating said element at intervals, a member adjustably mounted upon said cam for varying the length of the intervals, and means for securing said member at any point of its adjustment. ¹⁵

In testimony whereof we affix our signatures.

JOHN T. WAYLAND.
TOM D. JONES.
